UNITED STATES PATENT OFFICE.

JOSEPH BECVAR, OF CLEVELAND, OHIO, ASSIGNOR TO THE WEHRLE COMPANY, OF NEWARK, OHIO, A CORPORATION OF OHIO.

DESIGN FOR A RANGE.

No. 38,974.

Specification for Design.

Patented Dec. 31, 1907.

Application filed November 21, 1907. Serial No. 403,225. Term of patent 7 years.

To all whom it may concern:

Be it known that I, JOSEPH BECVAR, a citizen of the United States, residing at Cleveland, in the county of Cuyahoga and State of Ohio, have invented a new, original, and ornamental Design for Ranges, of which the following is a specification, reference being had to the accompanying drawing, forming a part thereof.

The figure is a perspective view of a range, showing my new design.

I claim:

The ornamental design for a range, as shown.

JOSEPH BECVAR.
